UNITED STATES PATENT OFFICE.

CHARLES A. TATUM, OF NEW YORK, N. Y.

FOUNTAIN-SYRINGE.

No. 806,306.

Specification of Letters Patent.

Patented Dec. 5, 1905.

Application filed August 23, 1905. Serial No. 275,347.

To all whom it may concern:

Be it known that I, CHARLES A. TATUM, a citizen of the United States, residing in the city, county, and State of New York, have 5 invented a new and useful Improvement in Fountain-Syringes, of which the following is a specification.

My invention relates to a fountain-syringe, the reservoir portion of which is so constructed that it may be opened to receive the tube, nozzles, and other accessories of a syringe and may then be closed so as to retain the same. The syringe thus forms its own package, making it of especial convenience for 15 travelers.

In the accompanying drawings, Figure I is a front view, partly broken away, of my syringe-reservoir closed and containing the tube and spray-nozzles. Fig. II is a portion of the 20 reservoir shown open in side view.

A is the syringe-reservoir, made of rubber or other waterproof material.

B B are pocket-book-closure U-frames of the usual construction, hinged at C and provided with ball-catches D D.

E is a chain for suspending the syringe. It is attached, preferably, to the hinge portions of the frames.

F is a hard-rubber nipple to which one end 30 of the tube G is attached when the syringe is in use, the other end of the tube being attached to one of the hard-rubber spray-pieces H.

The operation of my device is as follows: The reservoir is opened by pressing apart the 35 U-frames B, the contents are removed, and one end of the rubber tube G is slipped over the nipple F and the other end over the nipple portion of one of the spray-pieces. Water or other liquid is then introduced into the 40 reservoir through the opening between the U-frames. After use the rubber tube G is removed from the nipple F and, together with the various spray-pieces and other accessories, placed into the reservoir, the latter 45 having first been opened by spreading apart the two U-frames. When the contents are in their proper place, the reservoir is closed by uniting the U-frames and the ball-clasps.

I claim as my invention—

1. In a fountain-syringe, a reservoir provided with a nipple at one end, and with hinged U-frames at the opposite end, and means for retaining the latter in a closed position.

2. In a fountain-syringe, a reservoir provided with a nipple at one end, and with two locking-frames hinged together, at the opposite end, and means for retaining said frames in a closed position.

In testimony whereof I have hereunto set 60 my hand, in the presence of two subscribing witnesses, this 21st day of August, 1905.

CHARLES A. TATUM.
